UNITED STATES PATENT OFFICE

139,998

DESIGN FOR A GLIDER AIRPLANE

Volmer S. Jensen, Glendale, Calif., assignor to
California Aero Glider Co. Inc., Los Angeles,
Calif.

Application March 18, 1944, Serial No. 112,952

Term of patent 14 years

(Cl. D71—1)

To all whom it may concern:

Be it known that I, Volmer S. Jensen, a citizen of the United States, a resident of Glendale, in the county of Los Angeles and State of California, have invented a new, original, and ornamental Design for a Glider Airplane, of which the following is a specification, reference being had to the accompanying drawings, forming part thereof.

Fig. 1 is a top plan view of a glider airplane showing my new design;

Fig. 2 is a front elevational view of the same;
Fig. 3 is the left side perspective view;

Fig. 4 is a perspective view of the airplane as shown from the front above the level of the wings; and

Figs. 5 and 6 are, respectively, rear perspective views of the airplane as it appears with the rear door in closed and open positions.

I claim:

The ornamental design for a glider airplane, as shown.

VOLMER S. JENSEN.
